UNITED STATES PATENT OFFICE.

PAUL KESTNER, OF LILLE, FRANCE, ASSIGNOR TO KESTNER EVAPORATOR COMPANY, OF PHILADELPHIA, PENNSYLVANIA, A CORPORATION OF PENNSYLVANIA.

PROCESS OF CONCENTRATING LIQUIDS.

965,822.

Specification of Letters Patent. Patented July 26, 1910.

Application filed May 29, 1906. Serial No. 319,386.

To all whom it may concern:

Be it known that I, PAUL KESTNER, a citizen of the French Republic, residing at Lille, in the Nord Province of France, 5 have invented an Improved Process of Concentrating Liquids, of which the following is a specification.

My invention relates to the concentration of liquids, and it consists of an improved 10 method or process of evaporation wherein I am enabled to secure a high degree of efficiency in an economical manner.

As is well known in the practice of evaporating liquids by bringing them adjacent to 15 or in contact with heated surfaces, better results are obtained by causing the liquid to flow in thin films or streams over said surfaces. Several attempts have been made to apply this principle in the operation of 20 tubular evaporators, for instance, by use of the structure shown in the British patent of Lillie, No. 12,391, dated August 28, 1888. In attempting to carry this process into 25 practice, however, more or less difficulty has been met with. Liquids flowing in a downward direction over heated surfaces tend to flow in streams and follow distinct paths or courses, and a portion of the evaporating surface is left naked or comparatively 30 naked and is not utilized. To remedy this defect, it has been suggested to considerably increase the volume of liquid circulated, but as such mode of procedure involves the employment of a pump capable of circulating a 35 much larger volume of liquid than can be concentrated in a single passage over such evaporating surface and therefore also involves employment of comparatively thick layers in lieu of films, this method of evapo- 40 ration has not been satisfactory, even with the most elaborate and ingenious arrangement of nozzles or other means for distributing the liquid to the evaporating surface or surfaces.

45 The improved method or process forming the subject of my invention insures the desired concentration of the liquid in a single passage through the apparatus, and as mechanical elevation of the liquid is unnecessary, no pump is required.

The theory upon which my improved method or process is based, is as follows: If, instead of allowing liquid simply to flow into the upper end of a vertical tube, with 50 or without distributing nozzles, a certain

volume of steam or vapor is continuously admitted along with the liquid and admixed therewith, then said liquid will be converted into a vesicular mass and will also be, almost continuously, evenly distributed in a thin 60 film over the whole of the interior surface of the tube and will flow with even regularity, wetting the whole surface.

In the accompanying sheet of drawings I have shown an evaporator or concentrating 65 apparatus by means of which my improved method or process may be carried out, in which:

Figure 1, is a vertical section of one form of complete apparatus embodying my invention; Fig. 2, is a cross-sectional view, taken on the line *a—a*, Fig. 1; Fig. 3, is a cross-sectional view, taken on the line *b—b*, Fig. 1, and Fig. 4, is a diagrammatic view of another form of apparatus embodying 75 my invention.

In Fig. 1, 1 represents a casing of suitable size in which a number of vertical tubes 2 and 3 are mounted; said tubes being disposed in two groups, the tubes 2 lying adjacent the wall of the casing and inclosing the tubes 3. Plates 4 and 5 are mounted at the top and bottom of said casing to receive said tubes; said plates forming the ends of the steam or heating chamber 6. The tubes pass 80 through and extend slightly above the upper plate 4, while their lower ends fit into the lower plate 5. Steam is introduced at 7 into the chamber 6, and the condensation therefrom runs off through a suitable outlet 85 at the level of the lower plate, (not shown). The casing is provided with a cap or cover 8, forming a chamber 9 between it and the upper plate 4, which chamber is common to both groups of tubes. 90

The liquid to be concentrated is fed continuously from any suitable source to the inlet 10 from which it passes into an annular chamber 11 with which the group of tubes 2, arranged adjacent the wall of the casing 1, are in communication. The liquid rises in the tubes 2 in the well known manner of film-climbing by the action of the vapor generated within the same from said liquid by the heat, being at first converted into a vesicular or foamy mass, with constantly 100 circulating and changing bubble-walls in contact with the inner walls of said tubes, and later becoming a climbing film which 105 overflows into the chamber 9. From the

chamber 9, such liquid descends, along with the vapor formed, through the central group of tubes 3, in which it is evenly distributed in a thin film upon the whole interior surface of each tube, as explained above, without following courses, and passes with the attendant commixed vapor into a separating chamber 12 upon which the casing 1 is mounted. In lieu of this arrangement, the central group of tubes may be employed for the climbing body of liquid and the outer tubes for the descending body; the feeding and delivery ends of the respective tubes being correspondingly changed. The chamber 12 is provided with an outlet 13 for the vapor.

A tubular extension 14 forms the discharge outlet for the pipes 3; such extension being within the separating chamber 20 and serving to direct the liquid and vapor onto a plate 15 having curved vanes 16 and forming a centrifugal separator whereby the liquid discharged upon the same is thrown outwardly against the sides of the separating chamber, while the attendant vapor escapes through the outlet 13. The concentrated liquid may be withdrawn from the separating chamber through the lower outlet 17.

30 As may be seen, the process is a combination of two stages. In the preliminary stage, a partial evaporation is obtained in the tubes 2, in which the liquid ascends. In this stage the raising of the liquid to the top 35 of the apparatus is accomplished, and, at the same time, the volume of vapor necessary for and essential to operation of the second and main stage of the process is formed or generated. In said second stage, the liquid 40 flows down the tubes 3 in a continuous film, completely filming and covering the surface of said tubes with the aid of the vapor formed in the liquid, and as this is the main stage of the process, the number of tubes for 45 the ascending liquid is only limited according to the volume of vapor required to be produced for the proper carrying out of the second and main stage of the process.

Although for the sake of simplicity it is 50 found advantageous to arrange the tubes for the ascending liquid in the same casing as the tubes for the descending liquid, as shown in Fig. 1, of the drawings, they may be placed in separate casings; that is to say, 55 there may be a separate evaporator for each stage; in the first of which there is provision for a preliminary or partial evaporation in which the liquid ascends and produces the necessary volume of vapor or steam, and a 60 second with tubes for the descent of the liquid for the main stage of the process; such for instance as illustrated in Fig. 4. In this structure, A represents a casing for 65 tubes 2^a in which the liquid to be concentrated ascends from an inlet 10^a; such casing

having an inlet 7^a for steam to circulate around said tubes 2^a and effect the raising of the liquid therein; means (not shown) being provided to remove the water of condensation from said casing. B is a casing containing tubes 3^a for the downward passage of the liquid to be concentrated; the upper ends of said casings having a communicating chamber 9^a whereby the liquid ascending in the tubes 2^a of the casing A may pass to and 70 overflow the projecting ends of the tubes 3^a of the casing B. The lower ends of the tubes 3^a communicate with a discharge section having a plate with curved vanes to receive the liquid whereby it is thrown against 75 the walls of the separating chamber while the attendant vapor finds its exit through a suitable outlet; this portion of the structure being the same and operating in a manner similar to the operation of the structure 80 shown in Fig. 1. Steam for the casing B to circulate around the tubes 3^a therein, may pass directly from the steam space of the casing A, through the pipe 18, as shown, or it may be supplied from an entirely independent source. 85

In the described process, employing either form of apparatus shown, a regulated supply of liquid is admitted at the base of a narrow heated tube or series of tubes and 90 enters into ebullition. The mixture of liquid and vapor, being specifically light rises upward, the proportion of vapor steadily increasing as the mixture rises. With a proper correlation between the supply of 95 liquid, the size of the tube or tubes and the amount of heat supplied, the liquid in the upper part of the tube or tubes becomes merely an annular, wall-climbing film carried forward by the onrush of a central column of vapor. As the proportion of vapor to liquid increases, so of course does the speed of travel of this current of vapor, the diameter of the tube or tubes not being increased, and, concomitantly, the power of 100 the current to maintain the travel of the film so that the film travels with substantial uniformity throughout the height of the tube or 105 tubes. In the lowermost extremity of the tube or tubes, the entering liquid is a solid 110 body which becomes a vesicular mass and finally is transformed into the described annular layer of liquid and center column of rushing vapor. Under these conditions, a maximum evaporative effect is secured since 115 the climbing film is very thin and is uniformly distributed over the hot walls. The feed of liquid is, of course, so maintained that this film persists throughout the height 120 of the tube or tubes, the feed being proportionate to the evaporation. The liquid and vapor emerge from the top of the tube or tubes with considerable velocity and in the downward progress through the next tube 125 or series of tubes, the gravitational progress of 130

the liquid is facilitated and made uniform by the action of the vapor. Under these conditions, the liquid does not tend to follow courses or paths, as would be normal to 5 a layer of liquid of the same thickness flowing under gravity alone, but is uniformly distributed over the tube walls. To produce these results, the conditions of heat and feed must of course be carefully regulated.

10 I claim:

1. The process of concentrating liquids, which consists in first causing a body of liquid to rise within a closed space under the influence of heat and of the vapor there- 15 by generated in said liquid, and then caus- ing said liquid together with its attendant vapor to descend within a closed space, the presence of the vapor causing the liquid to form substantially continuous thin films 20 within said closed spaces in both ascent and descent whereby concentration of the same is facilitated.

2. The process of concentrating liquids, which consists in introducing a body of liquid at the base of a series of tubes, applying heat to said tubes whereby the liquid therein is vaporized and caused to ascend in a film covering the inner surface of said tubes, allowing said partially concentrated 30 liquid together with its attendant vapor to pass to a second series of tubes for a downward passage, and applying heat to said latter tubes whereby the vaporization continues and the liquid is caused to cover the inner 35 surface of said tubes in both ascent and descent thereby producing an even flow and concentration of the same.

3. The process of concentrating liquids, which consists in introducing a body of 40 liquid at the base of a closed space, applying heat to said closed space whereby the liquid within the same is caused to vaporize in part and the residue to ascend therein as a climbing film, allowing said partially concen- 45 trated liquid to pass to a second closed space wherein it moves downward, heating said second closed space whereby the vaporization continues, the vapor developed in both spaces serving to cause the liquid to con- 50 tinuously film within said second closed space to facilitate the downward flow and concentration of the same, and discharging the concentrated liquid under such conditions as to effect separation of the same from 55 the entrained vapor.

4. The process of concentrating liquids, which consists in introducing a body of liquid at the base of a series of tubes, heating said tubes whereby the liquid is caused 60 to partially vaporize and the residue to climb in said tubes, allowing said liquid together with its attendant vapor to pass to and descend in a series of separate heated tubes, the vapor or steam produced causing

an even distribution of the liquid in con- 65 tinuous traveling films over substantially the whole inner surface of both sets of tubes in both ascent and descent.

5. The process of concentrating liquids, which consists in circulating them in two 70 directions in vertical passages, first in an ascending column, and second in a descending column, supplying heat to said passages whereby said liquid is caused to form vapor or steam and effect movement of the liquid, 75 said attendant vapor or steam serving to cause the liquid to wet and film the surfaces of both passages and induce the flow of even and substantially continuous traveling films of the liquid in both directions. 80

6. The process of concentrating liquids, which consists in passing the same in ascending and descending columns out of contact with each other, and heating said columns whereby said liquid is vaporized, substan- 85 tially the entire volume of vapor thus created accompanying and effecting the ascent and assisting descent of said columns of liquid.

7. The process of concentrating liquids, 90 which consists in passing the same in oppo- sitely directed vertical streams out of contact with each other, and supplying heat to said streams of liquid, the ascending stream of liquid being automatically induced by the 95 vapor produced therefrom by such heat, and substantially the whole volume of vapor thus created accompanying and inducing the descending stream to film and assisting the proper downward flow of the same. 100

8. The process of concentrating liquids, which consists in heating the same to such a degree that steam or vapor is formed, then conducting such liquid together with sub- 105 stantially the whole volume of its attendant vapor to a series of externally heated tubes for downward passage therein, the attendant vapor causing the liquid to film-cover the entire surface of said tubes in both ascent and descent, thereby facilitating the downward flow and concentration of the same, 110 and then separating the liquid and vapor at the discharge end of said tubes.

9. The process of concentrating liquids, which consists in first lifting said liquid by 115 heat and the vapor generated thereby in a filmiform body, and then passing said liquid by and with its attendant vapor in a sub- stantially continuous thin film over a heated surface whereby concentration of the same 120 is facilitated.

In testimony whereof I have signed my name to this specification in the presence of two subscribing witnesses.

PAUL KESTNER.
